HOLDING PLATE FOR A CLIP OR THE LIKE

Frank Stanley Schade, Holyoke, Mass., assignor, by mesne assignments, to National Blank Book Company, Inc., Holyoke, Mass., a corporation of Nevada

Filed Feb. 27, 1967, Ser. No. 5,961

Term of patent 14 years

(Cl. D74—2)

FIG. 1 is a perspective view from the front of a holding plate for a clip or the like showing my new design;

FIG. 2 is a side elevation thereof, the opposite side being a mirror image of FIG. 2;

FIG. 3 is a front elevation thereof; and

FIG. 4 is a rear elevation thereof.

The dominant features of the new design reside in the portions shown in full lines with other portions of the clip and part of a clipboard being shown in broken lines in FIGS. 1 and 2 for illustrative purposes only.

I claim:

The ornamental design for a holding plate for a clip or the like, as shown and described.
